John Straub, INVENTOR.

BY

Geo. P. Kimmel.

ATTORNEY.

UNITED STATES PATENT OFFICE.

JOHN STRAUB, OF ASHLEY, NORTH DAKOTA.

TELEPHONE STAND OR EQUIPMENT.

Application filed July 29, 1926. Serial No. 125,746.

This invention relates to telephone structures and pertains particularly to an improved type of telephone receiver and means associated therewith for holding or releasing 5 the hook arm upon which such receivers are ordinarily supported.

The primary object of this invention is the provision, in a manner as hereinafter set forth of a telephone structure having the 10 receiver thereof pivotally secured to one side of the structure and having associated therewith a swinging member designed to hold down the contact arm when the receiver is not in use.

15 The invention herein set forth is designed to eliminate the trouble and bother of holding a telephone receiver in the hand during the course of a telephone conversation and aims to adjustably fix the receiver to the telephone body in such manner that the speaker at the phone can stand with the ear in close proximity to the receiver without having to hold the same thus leaving the hands free for writing or for other purposes and at the same time allowing the use 20 of the phone without tiring the user by holding a receiver.

25 The invention will be best understood from a consideration of the following detailed description taken in connection with the accompanying drawings forming a part of this specification, with the understanding, however, that the invention is not confined to any strict conformity with the showing 30 of the drawings but the same may be changed or modified so long as such changes or modifications mark no material departure from the salient features of the invention as expressed in the appended claim.

35 In the drawings:

Figure 1 shows a telephone and supporting stand therefor in side elevation.

Figure 2 shows the same structure in elevation from the opposite side thereof and,

40 Figure 3 shows a front elevation of the structure and the device embodying this invention applied thereto.

45 Referring now to the drawings in detail wherein like numerals of reference indicate corresponding parts throughout the several views, there is indicated by the numerals 1 a pair of upright members having forwardly and rearwardly extending foot portions 2 supported by castors 3.

50 These upright members 1 are connected at

the bottom by the cross rail 4 and at their central portions by the inclined outwardly extending board 5 which constitutes a writing surface or desk. The lower edge of the desk is provided with the usual guard rail 6. The upper ends of the standard 1 are connected by the relatively wide panel 7 upon the central portion of which is mounted a phone box 8 of the usual construction, the same being provided with the bell 9, the transmitter 10 and the ringing crank 11.

From the opposite side of the phone box 8 from the crank 11, there extends in the place of the usual receiver supporting hook, 70 the arm 12. This arm acts in the same capacity as the usual receiver supporting hook except that the hook portion at the end is not provided.

Pivotaly mounted upon the side of the box 8 from which the arm 12 extends, is a plate member 13 which is pivoted at the point 14, this pivotal point being intermediate the ends of the plate. The lower portion 15 of the plate 13, has an outwardly 75 extending lug 16 to which a spring 17 is attached. The other end of this spring is secured in any suitable manner to the telephone box 8, as indicated by the numeral 18. From the showing of Figure 2 80 taken together with the description, it will be readily seen that due to the spring 17 the upper portion of the plate 13 will always be thrown inwardly against the bar 12.

The upper portion of the plate 13 has 85 a rearwardly extending bill 19 formed thereon, thus setting up a hook which engages over the arm 12 in the manner shown in Figure 2. The arm 12 is thus prevented from moving upwardly until the bill 19 is 90 removed from over the arm. An operating button 20 is secured to the upper end of the plate 13, by means of which the phone user can easily and quickly catch hold of the plate and draw the same forwardly to 95 release the lever 12.

Upon the side of the phone box 8 beneath the lever 12, there is pivotally mounted a receiver member indicated generally by the numeral 21. This receiver member is 100 formed in two portions, which portions are in substantially right angular relation, the portion 22 having the reproducing mechanism in the outer end thereof and being normally directed forwardly of the phone 105 110

box 8. The other portion 23 is directed inwardly toward the side of the phone box 8 and is secured thereto by means of the collar 24, which collar is secured to the phone box. The inwardly directed end of the portion 23 is pivotally secured in the collar 24 so that the portion 22 of the receiver can be swung upwardly or downwardly and will remain in any adjusted position.

In the use of this phone structure a person answering the ring of the phone bell, adjusts the receiver 21 to the proper height, if it has not been formerly properly adjusted, and then grasping the button 20 of the plate 13, draws the plate forwardly. This releases the bar or arm 12 and thus operates the phone mechanism in the same manner as when in the usual structure the receiver is lifted from the receiver hook. After using the phone, the plate 13 is again drawn forwardly and the arm pulled down whereupon the plate is released to allow the bill 19 to swing back over the arm, and the parties will be cut off.

Having thus described my invention what I claim is:

In combination, a telephone box including a receiver arm switch projecting through one side thereof and adapted for vertical movement, a substantially L-shaped receiver having one arm extended laterally from and pivotally supported by said side and its other arm projecting forwardly of said side, a transmitter connected to the front of the box, a vertically disposed latch pivoted intermediate its ends to said side in proximity to said switch, positioned over the pivoted end of the receiver and having at its upper end a rearwardly extending bill movable into the path of movement of said switch arm to latch it in lowered position, a spring connected with the lower end of the latch and to said side of the box and normally acting to maintain said bill in the path of said switch, and a finger engaging lateral extension on the latch at its upper end, forwardly of the bill above the receiver and accessible from the front of the box.

In testimony whereof, I affix my signature hereto.

JOHN STRAUB.
